ATTORNEY

WITNESS: *John Donovan*

UNITED STATES PATENT OFFICE.

JAMES MANIAS, OF GLENS FALLS, NEW YORK, ASSIGNOR OF ONE-HALF TO GUST D. GOLUSES, OF GLENS FALLS, NEW YORK.

AUTOMATIC FUSE.

Application filed June 27, 1924. Serial No. 722,771.

To all whom it may concern:

Be it known that I, JAMES MANIAS, a citizen of Greece, residing at Glens Falls, in the county of Warren and State of New York, have invented new and useful Improvements in Automatic Fuses, of which the following is a specification.

The object of my said invention is the provision of a peculiar and advantageous automatic repeating fuse for use in electric connections.

To the attainment of the foregoing, the invention consists in the improvement as hereinafter described and definitely claimed.

15 In the accompanying drawing, forming part of this specification:—

Figure 1 is an end view of my novel fuse.

Figure 2 is a diametrical section of the fuse on the line 2—2 of Figure 1.

20 Figure 3 is a diametrical section taken in the plane indicated by the line 3—3 of Figure 2.

Figure 4 is an end view of the fuse with the closure means removed.

25 Figure 5 is a detail perspective of the terminal carrying member of my improvement.

Similar numerals of reference designate corresponding parts in all of the views of the drawing.

30 Among other elements my novel fuse comprises a body 1 of insulating material, closed at one end and open at its opposite end and having adjacent to its closed end a threaded portion 2 covered by conductive material 3 and designed to be turned into an appropriate socket (not shown). In the closed end of the body 1 is a screw 4 on which is a nut 5 for securing on the screw one end of a spring terminal 6 that tends to snap or

40 move in the direction indicated by arrow in Figure 2.

The terminal carrying member 7 of my improvement is formed in one piece of light weight tin or equivalent material, and comprises a body 8 on which is a lug 9, and terminals 10, the said terminals 10 being twisted where they join the body 8 so that the terminals will rest at right angles to the body 8, Figures 3 and 5. The body 8 of the member 7 rests over a conductive member 10¹, and the lug 9 rests back of the said member 10¹, while the terminals 10 are arranged in a series at right angles to the spring terminal 6 so that when the terminal 10 at the right 55 of Figure 2 burns out the spring terminal

6 will snap or spring to the next terminal 10 toward the left and so on until all of the several terminals are used in succession. Manifestly when the member 7 is completely burned out it may be expeditiously 60 and easily removed and as readily replaced with a new member 7.

Arranged over the open end of the body 1 is a transparent disk 11 of appropriate material, and arranged over the said disk 65 11 is a closure cap 12 slotted at 13 to display the spring terminal 6 and the several terminals 10, and provided by preference with numerals indicating the several terminals 10. It will also be noticed that the cap 12 is flanged at 14 to detachably secure it on the comparatively large portion of the body 1.

Interposed between the conductive member 10¹ and the conductive covering 3 is a conductor 15 that is contained within the insulating body 1 of the fuse.

As best shown in Figures 2 and 3 the body 1 is notched at 16 to seat the free ends of the terminals 10 and consequently lateral deflection of the said terminals 10 because of pressure exerted by the spring terminal 1 will be effectively prevented.

It will also be observed that by viewing the fuse through the slot 13 of the cap 12, a party interested can readily ascertain how many of the terminals 10 of the fuse remain intact.

Notwithstanding the practical advantages of my novel fuse it will be manifest that the same is simple and inexpensive in construction and is well adapted to withstand the usage to which fuses are ordinarily subjected.

I have specifically described the preferred embodiment of my invention in order to impart a definite understanding of the said embodiment in all of its details. I do not desire, however, to be understood as confining myself to the said specific construction inasmuch as my invention is defined by my appended claims and within the scope of said claims changes or modifications may be made without involving departure from my invention.

Having described my invention, what I claim and desire to secure by Letters-Patent, is:—

1. A repeating fuse comprising a hollow body of insulating material open at one end 110

and closed at its opposite end and having adjacent to its latter end a conductive covering, a spring terminal connected to the closed end of the body, a conductive member arranged in the open end of the body and electrically connected by an interior conductor with the said conductive covering, a terminal carrying member resting over the said conductive member and having a lug back of the same and also having a plurality of spaced terminals intersecting the path of the free end of the spring terminal, a transparent disk opposed to the open end of the body and arranged over the terminal carrying member, and a closure cap arranged over said disk and secured on the body and having a slot for the display of the terminals.

2. A repeating fuse comprising a hollow body of insulating material open at one end and closed at its opposite end and having adjacent to its latter end a conductive covering, a spring terminal connected to the closed end of the body, a conductive member arranged in the open end of the body and electrically connected by an interior conductor with the said conductive covering, a terminal carrying member resting over the said conductive member and having a lug back of the same and also having a plurality of spaced terminals intersecting the path of the free end of the spring terminal, a transparent disk opposed to the open end of the body and arranged over the terminal carrying member, and a closure cap arranged over said disk and secured on the body and having a slot for the display of the terminals; the said body being provided with notches, and the free ends of the said terminals of the terminal carrying member being disposed in said notches.

In testimony whereof I affix my signature.

JAMES MANIAS.
